VALVE SPRING COMPRESSOR

Emil Jensen, Union Grove, Wis.

Application April 29, 1949, Serial No. 90,395

1 Claim. (Cl. 29—219)

1

This invention relates to valve spring compressors for Ford mushroom end valves or similar valves and the object of the invention is to provide a valve spring compressor consisting of only two pieces which are adapted to be easily and readily assembled and disassembled.

Another object of the invention is to provide a valve spring compressor of the character indicated above comprising a holder adapted to receive a valve assembly therein and a hand lever removably and adjustably mounted on said holder and adapted to engage either end of the valve stem and to compress the valve spring to facilitate the removal or replacement of the spring retainer commonly used in connection with valves of the kind indicated above or similar valves.

A further object of the invention is to provide a valve spring compressor of the character indicated above adapted to center the valve stem with regard to the valve spring during the process of compressing said spring.

The invention consists in the details of construction and in the combination and arrangement of the several parts of my improved valve spring compressors whereby certain advantages are attained, as will be hereinafter more fully set forth.

In order that my invention may be better understood, I will now proceed to describe the same with reference to the accompanying drawings, wherein:

Figure 1 is a view in front perspective of a holder constructed in accordance with an embodiment of the invention;

Figure 2 is a view in perspective of an abutment tool as herein embodied;

Figure 3 is a view in front elevation with a portion in section illustrating a valve assembly within the holder and before compression of the spring, the associated lever in fragment and perspective;

Figure 4 is a view similar to Figure 3 but showing the spring compressed;

Figure 5 is a view similar to Figure 4 but with the valve assembly reversely applied;

Figure 6 is an elevation view of a modified form of the invention;

Figure 7 is a fragmentary view in top plan of the holder as comprised in Figure 6; and

Figure 8 is a fragmentary view in perspective of an end portion of the lever herein embodied.

The valve spring compressor as embodied in Figures 1 to 5 comprises a holder H having a semi-cylindrical portion 10 adapted to receive the

2

tapped end portion 11 of the valve stem 12 of a Ford mushroom end valve V or a similar valve with the helical spring 13 and the guide bushing 14 mounted on said valve stem. To accommodate the valve head 15 the holder H has an enlarged semi-cylindrical portion 16 of longer radius than the first named holder portion 10. The two semi-cylindrical holder portions 10 and 16 are permanently connected with each other by means of a half conical intermediate portion 17 and form an integral coaxial unit.

A pair of flanges 18 is formed on the outer end of the narrower holder portion 10. These flanges project toward each other and the distance between the flange edges facing each other is such that the spring retainer 19 commonly used in connection with valves of the kind indicated above can be slid into the space between the two flanges and the end coil of the spring 13 abuts the flanges 18.

A hand lever 20 is preferably made from flat iron and has a lever head 21 and an elongated lever handle 22. The lever head 21 extends in a substantially right angle from the lever handle but is curved so that the inner surface of the head is convex. On the end portion of the lever head a centrally located finger 23 is formed the outer end portion 24 of which extends inwardly at an obtuse angle.

30 A plurality of preferably rectangular holes 25 are arranged in the enlarged holder portion 16 adjacent to a longitudinal edge thereof.

When the spring retainer 19 is to be removed from the valve stem 12, the valve assembly is placed in the holder H in the position shown in Figure 3. The lever 20 is mounted on the holder H by inserting the finger 23 through a selected hole 25. By gripping the holder H and the lever handle 22 and forcibly pivoting the latter toward the former the curved lever head 21 engaging the valve head 15 urges said valve head toward the narrower holder portion 10. The flange 26 conventionally formed on the valve stem 12 adjacent to the valve head 15 engages the guide bushing 14 which in turn engages and compresses the valve spring 13, so that the tapped end 11 of the valve stem will slide outwardly from the holder H and the spring retainer 19 may be removed easily and readily. By releasing the pressure on the lever 20 the valve assembly is released and may be easily disassembled.

By mounting a guide bushing 14 and a valve spring 13 on a valve stem 12, arranging these assembled parts in a holder and compressing the spring in the manner described above, a spring

retainer 19 may be easily mounted on the valve stem 12 completing the assembly of the valve.

When an assembled valve of the kind described is to be mounted in a motor a well known removable abutment tool 27 is arranged on the valve stem 12 between the guide bushing 14 and the flange 26. In order to facilitate this arrangement the valve assembly is placed in the holder H so that the valve head 15 is located outside of the holder adjacent to the flanged end of the narrower portion thereof. The tapped end 11 of the valve stem 12 is engaged by the curved lever head 21. The bushing 14 is forced against the flanges 18 and the spring 13 is compressed so that the valve stem 12 slides through the bushing and the stem flange 26 is spaced from the bushing permitting the arrangement of the abutment tool 27 on the valve stem 12 between the stem flange 26 and the bushing 14. When the pressure on the lever handle 22 is released the tool is held removably in position by the pressure of the spring 13 on the guide bushing 14.

In Figure 6 a slightly modified form of the holder for valve spring compressors in accordance with the present invention is shown. The holder as embodied in Figure 6 has a semi-cylindrical portion 28 similar to the holder portion 10, an enlarged holder portion 29 similar to the holder portion 16 and a half conical intermediate holder portion 30 similar to the intermediate holder portion 17.

The outer end portion of the narrower holder portion 28 is offset so that one-half of said end portion extends beyond the other half as indicated at 31. On the outer end of the longer half of the holder end portion an inwardly projecting flange 32 is formed, the inner edge surface of which is concaved as at 33 to conform to the contour of the valve stem 12 and the flange 32 is long enough to extend between two coils of the spring 13 and to engage the valve stem 12 and hold it in central position with respect to the spring 13. On the shorter end portion of the holder portion 28 an inwardly projecting flange 34 is formed similar to the flanges 18 and adapted to project between a pair of coils of the spring 13 located inwardly from the coils engaged by the flange 32.

The hand lever 20 is adapted to be used in connection with either form of the holder and the second form is used if it is desired to center the stem relative to the spring and to allow more room for the removal of the retainer 19.

From the foregoing description it is thought to be obvious that a valve spring compressor constructed in accordance with my invention is particularly well adapted for use by reason of the convenience and facility with which it may be assembled and operated.

I claim:

In a valve spring compressor, a holder comprising an upper semi-cylindrical portion, an intermediate outwardly flared portion and a lower semi-cylindrical portion, a semi-circular flange inturned from the top end of said upper portion, said lower portion having a vertically aligned set of spaced slotted openings formed adjacent one of its vertical edges, a hand lever having an elongated handle portion normally disposed vertically alongside the holder, and an arcuate head portion bent at right angles from the lower end of said handle portion, the free end of said head portion being adapted to be selectively engaged in said slotted openings to fulcrum on the lower edge of the engaged opening to affect compression of the valve spring between the arcuate portion of said head portion and said flange, when the handle portion of said lever is swung outward and downward relatively to the holder, the connected end portion of said head portion having sliding contact with the other vertical edge of the lower portion of the holder during the operative movements of said lever.

EMIL JENSEN.
